CARCASS-TREATING METHOD

Application filed March 3, 1928. Serial No. 258,922.

This invention relates to the surface treatment of edible carcasses and more especially to methods of removing hair, bristles, feathers or other dermal excrescences and extraneous material. Heretofore, and at present, a good deal of trouble is often encountered in removing certain of these excrescences, particularly the so-called "hard" hair on hog carcasses. The usual method of scalding and then scraping or "polishing" usually suffices to remove the greater part of the hair but it is sometimes found practically impossible to remove all of these hairs by such methods and in consequence shaving or singeing certain parts of the carcass is sometimes resorted to. It is important to note, however, that any hair remaining on the carcass or any hair "roots" or stubs remaining after shaving results in rating the corresponding cuts downward in market value, only clean hairless cuts commanding a high rating and corresponding price.

The main objects of this invention are to provide an improved and simplified process for removing from food carcasses all of the hair or other dermal excrescences in their entirety; to do this with absolute thoroughness and without producing any undesirable effect on the carcass; to provide for practicing such a process by mechanical power means; to provide a method step in such a process which consists in beating off from the carcass a hard adhesive coating material in which the excrescences and extraneous material are to some extent embedded; to provide for thus removing such coatings consisting of any of the materials or compounds adapted for such use, as for example a mixture of resin, pitch and paraffine; to minimize all manual labor in connection with such treatment of carcasses as far as possible; and to provide such a method adapted for carrying out by unskilled workmen.

An illustrative embodiment of this invention and certain modifications thereof are shown by the accompanying drawings in which:

Figure 1 is a cartographic diagram setting forth the essential steps and indicating

certain preferred accessory features of the invention.

Fig. 2 is a conventional view illustrating how the carcass may be transferred or moved about from one operating section or zone to another, and also shows two methods of applying an adhesive coating, one mechanical and the other manual, the latter sometimes being supplemental to the other.

Fig. 3 is a conventional view showing how the coating may be broken up and stripped off, together with the adhering hairs and similar excrescences by a manually supported power operated beater.

Fig. 4 is a view of the discharge end of a large wholly automatic power driven carcass receiving rotary drum and beater.

Fig. 5 is a side view of the device shown in Fig. 4.

Fig. 6 is an enlarged detail of one of the beater arms of Fig. 4.

Referring now to Fig. 2, the carcass 1, represented in this instance by a hog, is carried by an overhead truck 2 traveling on the rail 3. A hard adhesive coating 4 is applied to the carcass by means of discharging spray 5 thereon from a nozzle 6. Such a nozzle is carried by a workman 7 who directs the spray manually, the nozzle being connected by a flexible pipe or hose 8 to a source of hot congealable liquid coating material maintained under pressure, but not here shown. Brief exposure of the coating to the atmosphere chills it sufficiently to harden, in which state it adheres tenaciously to the hair or bristles. Setting or hardening of the thermo-responsive material may be expedited if desired, as by a draft of air, water spray or by dipping the coated carcass in water, but this is not essential.

It is sometimes found desirable to supplement the work of the spray nozzle by manual application of additional coating material with a hand brush 9, as by an assistant workman who carries a pail 10 containing some of the hot coating material. It is to be understood that the coating as a whole may be applied entirely by hand, if desired in any instance, but on account of much greater speed and saving of labor, the spray method

is highly advantageous and generally preferable.

Fig. 3 is included mainly to illustrate the theory of mechanical beating of the carcass for removal of the coating and hairs, it being understood that a preferred embodiment of the beating method is illustrated by Figs. 4 and 5. However, the device in Fig. 3 may be used as an accessory for supplementing or finishing the work of the large drum and beater device of Fig. 4 in case any parts of the coating and hair remain after the carcass has passed through the drum.

Referring more in detail to Fig. 3, the beater comprises a rotary hub 15 journaled on the end of the handle bar 16, which is carried by the workman. Said hub is provided with a peripheral series of flexible outstanding straps 17 having hard masses of metal or the like attached to their extremities, preferably in the form of short strips or bars 18 riveted to the ends of the straps. This beater is driven at high speed by means of a flexible shaft 19 extending through the handle part 16 and connected to a source of power, as for instance an electric motor, not shown.

Referring next to Figs. 4 and 5, the machine 20 as a whole comprises a frame 21 having a receiving platform 22, a delivery platform 23 and a long rotary drum 24 axled nearly horizontally on said frame but inclined downward slightly from the receiving end to the delivery end. There is also journaled on said frame a shaft 25 having a pulley 26 on one end adapted to be belt driven from any desired source of power. Said shaft is geared at 27 for driving said drum directly. Longitudinally disposed in said drum and somewhat eccentric relative thereto is a rotary beater shaft 28 carrying a longitudinally arranged series of co-rotary beaters 29.

Referring to Fig. 4, it will be seen that the beater shaft 28 is somewhat below and to the left of the main axis of the drum 24. Said shaft, which is journaled at its ends on said frame 21, is mechanically connected to the shaft 25 by means of a belt or sprocket chain 31, said shafts having corresponding pulleys or sprocket wheels 32 and 33 respectively to receive the same.

Each of the beaters 29 comprises a hub 34 fixed on the shaft 28 and each hub is provided with a plurality of rigid arms 35 having flexible straps 36 attached thereto and said straps having solid beater elements 37 attached to their outer ends, preferably consisting of short radial strips of iron having their outer tips 38 inclined somewhat in the direction of rotation, the more effectually to engage and tear off the coating 4.

For the best practical results, we find it best to drive the shaft 25, at about 110 revolutions per minute, the accessory gearing be-

ing adapted and arranged to drive the barrel or drum 24 at about 15 revolutions per minute and the beater shaft 28 at about 250 revolutions per minute, the diameter of the drum 24 being about five and one-half feet, with a length of sixteen feet and a slope of two inches in its whole length. Furthermore, the drum and beater are driven in opposite directions, so that as the carcass is carried up somewhat on the ascending side of the drum and under the eccentrically positioned beater, the whipping and pulling action of the beater assists gravity in rolling the carcass over and over as it is gradually fed by gravity down the slight incline through the said drum. The beater elements 38 strike the carcass with sufficient violence to tear away all of the coating together with the hair and other extraneous matter.

It is to be understood that our invention is not limited to the use of any specific congealable liquid coating material or compound but applies to any and all coatings adapted for the process claimed. For instance, we may use a mixture of 9 to 12 per cent of cottonseed oil with a complement of 88 to 91 per cent of resin; or we may use a mixture of about 75 per cent of asphalt with about 25 per cent of resin. The latter mixture costs about four cents per pound. We may also use a mixture of about 30 per cent of pitch, 65 per cent of resin and 5 per cent of paraffine.

Although certain specific embodiments of apparatus and corresponding details of method comprised by our improvements have been selected to illustrate the invention herein set forth, it is to be understood that some of the details of the constructions shown and of the operative steps may be altered or omitted without departing from the spirit of this invention as defined by the following claims.

We claim:

1. The method of removing dermal excrescences from an edible carcass, including the part which is embedded in the skin, which consists in coating the carcass with an adhesive and temperature-responsive congealable liquid, chilling the coating to cause it to solidify and grip the excrescences, and then beating the coated surface of the carcass, whereby the indurated coating is removed together with the excrescences embedded therein.

2. The method of treating an edible carcass for removal of dermal excrescences therefrom, which consists in applying thereto a coating of temperature-responsive material in hot and fused condition, exposing the carcass to a relatively cold medium and thereby chilling the coating and so causing it to set, and then beating the carcass to remove the indurated coating together with the dermal excrescences embedded therein.

3. The method of treating an edible carcass which consists in applying thereto a coating of hot adhesive liquid, exposing the liquid-treated carcass to ordinary room temperature and thereby causing the liquid coating to set, and then removing the indurated coating, together with the dermal excrescences, by beating the carcass.

4. The method of treating a carcass which consists in spraying it with hot congealable liquid of adhesive character, exposing the carcass to a cooling medium whereby a hard coating is formed, and then beating the carcass to remove the coating together with whatever dermal excrescences are embedded therein.

5. The method of treating a carcass which consists in spraying it with hot congealable liquid of adhesive character, exposing the carcass to a cooling medium whereby a hard coating is formed, and then submitting the carcass to the action of a mechanical beater whereby the indurated coating is torn to pieces and removed, together with all dermal excrescences embedded therein.

6. The method of removing dermal excrescences from edible carcasses which consists in applying heat to loosen the excrescences, then coating the carcass with a hot congealable liquid of adhesive character, then chilling the coating to harden the same, and finally submitting the carcass to a rain of blows from light-weight, high-speed beaters whereby the coating is broken or shredded and removed together with the excrescences embedded therein.

Signed at Kansas City, Kansas, 23rd day of February 1928.
